UNITED STATES PATENT OFFICE.

GREGORY CALDWELL DAVISON, OF GROTON, CONNECTICUT.

DELAYED-ACTION FUSE.

1,311,054.

Specification of Letters Patent. Patented July 22, 1919.

Application filed August 8, 1918. Serial No. 248,906.

To all whom it may concern:

Be it known that I, GREGORY C. DAVISON, a citizen of the United States, residing at Groton, in the county of New London and State of Connecticut, have invented certain new and useful Improvements in Delayed-Action Fuses; and I do hereby declare the following to be a full, clear, and exact description of the invention, such as will enable others skilled in the art to which it appertains to make and use the same.

The present invention relates to improvements in delayed action fuses, and it is intended to provide a fuse in which action may be delayed for a short but predetermined interval of time after the projectile strikes the target, or the water, or the earth, as the case may be.

Attempts to secure such delayed action have hitherto been made by using trains of comparatively slow burning powder, clock-work, or other devices, but none of these, as far as I am aware, embodies the principle and advantage of the invention herein described.

It has been difficult to secure the proper time interval between the impact of the projectile and the ignition or detonation of the explosive charge contained therein.

I have found that by attaching to the fuse of ordinary construction a small chamber partly filled with powder of a suitable type, and having the walls of this chamber of sufficient thickness, there will be an appreciable interval between the time that the powder was ignited in said chamber and the time that the chamber is disrupted and the flame from said powder is applied to the bursting charge of the projectile.

I have also discovered that this time interval may be varied by varying the amount of powder and also by varying the quality of the powder used in said chamber. Thus, with a chamber of given strength and capacity, the action is slower where only a small amount of powder is contained therein and more rapid where the chamber is nearly full of powder.

Again, the action is more rapid with fine grain powder than with coarser grain powder.

By determining the amount of powder to be used and the quality of powder, a time interval may be secured which is substan-

tially uniform and sufficient for practical purposes.

If it is desired, I may supplement this ignition chamber just referred to with fulminate or other material used for detonating high explosive shells.

My invention is especially suitable for use with projectiles dropped or fired from aeroplanes, where it is desired to explode the projectiles after a predetermined depth in the water has been reached.

In Figure 1 of the drawings I have shown a fuse provided with the delayed action attachment and mounted in a shell adapted for firing from the Davis non-recoil gun, the said shell being described in the application of Andrew J. Stone, Serial No. 178,878, filed July 3, 1917, and entitled "Projectiles for use against submarines and submerged mines".

The ignition chamber may be attached to almost any of the well known types of percussion fuse.

My invention will be more fully understood after reference to the accompanying drawings, in which like parts are indicated by similar reference symbols throughout the several views, and in which:

Fig. 1 shows a central longitudinal section through the projectile and fuse, the ignition charge in the projectile being omitted, and parts of the fuse being shown in elevation.

Fig. 2 is a section, on a smaller scale, through the ignition chamber, adapted to be attached to the fuse.

Figs. 3 and 4 show modifications similar to Fig. 2, in which fulminate or other detonating material is also contained in the ignition chamber.

Fig. 5 shows a section through a modified form of fuse comprising the ignition chamber as herein described.

Figs. 6 and 7 show modifications similar to those shown in Figs. 3 and 4.

Referring first to Fig. 1, A represents the body of the projectile, which may be of either the type shown or of any suitable preferred type provided with the usual chamber to receive the bursting charge, which bursting charge is omitted from the accompanying drawings.

B represents the fuse stock which carries the plunger or other operating device C for

exploding the primer *d* carried in the block *D* secured in the end of the fuse. This block *D* is perforated to permit the passage of the flame from the primer to the powder charge *F* in the ignition chamber *E*, which is provided with internal screw threads *e* engaging the external screw threads *d'* on the block *D*.

By having this ignition chamber of sufficient strength, and using the proper charge of powder, which can best be determined by experiment, there is an appreciable interval between the time that the primer explodes and the time the flame is transmitted to the bursting charge of the projectile.

In the modification shown in Figs. 2, 3, and 4, the ignition chamber *E* is provided with internal screw threads *e*, by means of which it may be attached to any suitable type of fuse, the rear end of the ignition chamber being closed by the primer plug *D'*, and the front end being also closed.

In the form of device shown in Fig. 3, in addition to the powder charge *F*, I provide a closed receptacle *G* filled with fulminate or other detonating material, the walls of which receptacle should be of sufficient thickness to resist the heat and pressure of the powder gases created in the ignition chamber *E'*.

In the construction shown in Fig. 4, I attach to the primer plug *D'* a strong closed tube *E'* partly filled with powder, and this tube is surrounded by fulminate or other detonating material *H*, the end of the ignition chamber being closed by the plug *I*.

Figs. 5, 6 and 7 show constructions similar to those shown in Figs. 2, 3 and 4, except that the ignition chamber is a continuation of the fuse stock, and the rear end of the fuse stock is closed by a screw cap *K*.

This fuse stock is internally screw threaded at *b* not only to engage the screw threads of the cap *K* but also to engage the screw threads on the primer block *D'*, which closes the rear end of the ignition chamber.

The operation of the device is as follows:

On striking the water or other target, the projectile is suddenly retarded in its flight, and the plunger flies forward and strikes the percussion cap. The flame from the percussion cap passes through the central aperture of the primer block into the ignition chamber, which contains a predetermined amount of explosive matter, such as fine black powder. The amount of such explosive matter regulates the time for the combustion in the chamber to take place until it reaches such a point that the pressure is sufficiently great to burst the chamber. Then the flame is propagated to the bursting charge in the shell proper.

Experiments have shown conclusively that with the ignition chamber completely filled, the delayed action is minimum, and by de-

creasing the amount of the explosive in ignition chamber, the time of bursting in the shell can be proportionately delayed; thus, by regulating the size, the thickness, and the material of the ignition case, and the character and amount of explosive carried with in this case, the time of explosion, after the projectile strikes the water or other target, can be regulated at will to any desired amount, even though the actual intervals of time employed be very minute.

For example, by changing the amount of the ignition charge in the fuse from 22 grains to 15 grains, the time of bursting of the envelop was changed from approximately two hundredths of a second to three hundredths of a second, and this time will enable the projectile to pass down through the water to a sufficient depth to accomplish the desired results before the projectile explodes.

In the same way this delayed action would enable the projectile to pass through the armored deck of a ship, and would also enable the projectile to bury itself in the earth or masonry before the projectile exploded.

A similar delay would take place before the receptacle containing the fulminate shown in Figs. 3, 4, 6 and 7 is crushed in by the powder gases, or before the receptacle was heated to a sufficient temperature to set off the fulminate.

While I have shown the various fuses as of the centrifugal type, it will be obvious that other well known types of percussion fuse may be used in connection with my invention, and I do not mean to limit the invention to details of construction except as particularly pointed out in the claims.

I claim:—

1. A delayed action attachment for shell fuses, comprising a strong envelop partly filled with gun powder and secured to the base of the fuse, with a passage for the flame from the primer into said envelop, substantially as described.

2. A delayed action attachment for shell fuses, comprising a strong envelop partly filled with gun powder and secured to the base of the fuse, with a passage for the flame from the primer into said envelop, and a strong receptacle containing fulminate or the like also contained in said envelop, substantially as described.

3. The combination with a percussion fuse provided with a primer block and primer, of a delayed action attachment therefor comprising a strong envelop partly filled with gun powder secured to the base of the fuse, said primer block being provided with a passage to permit the flame from said primer to enter said envelop, substantially as described.

4. The combination with a percussion fuse provided with a primer block and primer,

- of a delayed action attachment therefor comprising a strong envelop partly filled with gun powder secured to the base of the fuse, said primer block being provided with a 5 passage to permit the flame from said primer to enter said envelop, and a strong receptacle containing fulminate or the like also contained in said envelop, substantially as described.
- 10 5. The method of securing delayed action for percussion shell fuses which consists in attaching to the base of the fuse a strong envelop partly filled with gun powder, and igniting this powder by the fuse causing the 15 said envelop to rupture at the end of the

time interval required by the pressure to reach the maximum needed, substantially as described.

6. The method of securing and adjusting the delayed action for percussion shell fuses 20 which consists in attaching to the base of the fuse a strong envelop partly filled with a predetermined charge of gun powder, and igniting this powder by the fuse causing the said envelop to rupture at the end of the 25 time interval required by the pressure to reach the maximum needed, substantially as described.

GREGORY CALDWELL DAVISON.
